(57) **CLAIM**

The ornamental design for a boat, as shown and described.

DESCRIPTION

FIG. 1 is a perspective view of a boat, showing my new design.

FIG. 2 is a first side elevational view of the boat of FIG. 1.

FIG. 3 is a second side elevational view of the boat of FIG. 1.

FIG. 4 is a top plan view of the boat of FIG. 1.

FIG. 5 is a front elevational view of the boat of FIG. 1; and,

FIG. 6 is a rear elevational view of the boat of FIG. 1.

The broken lines are included for the purpose of illustrating environmental structure and form no part of the claimed design.

1 Claim, 6 Drawing Sheets
